UNITED STATES PATENT OFFICE.

FRANK E. ROBINSON, OF NEW YORK, N. Y.

BINDER FOR LEAVES.

SPECIFICATION forming part of Letters Patent No. 600,975, dated June 21, 1898.

Application filed July 1, 1896. Serial No. 597,678. (No model.)

To all whom it may concern:

Be it known that I, FRANK E. ROBINSON, a citizen of the United States, and a resident of New York, in the county and State of New York, have made certain new and useful Improvements in Binders for Leaves, of which the following is a specification.

My invention is an improvement in binders for securing and holding single leaves, sheets, or blanks such as are employed for recording commercial orders for goods and similar purposes.

The object of my invention is to provide an inexpensive, durable, and effective binder for order-blanks which shall be so constructed as to receive and hold any number or varying numbers of leaves, and to further provide means for removing and replacing any single blank without disturbing or removing any of the other blanks of the series.

I provide a back board or frame or support about the size of the blanks or leaves to be bound or held, although it may be considerably larger. At or near one edge—say the top edge—I fix two iron rods or posts projecting vertically. I provide a cover, top board, or strip, having holes or perforations through which the rods or posts easily pass—that is, so as to permit the said top piece to slide freely on said rods or posts. Upon this top piece, cover, or strip I place two hinged or pivoted levers. The free or engaging ends of each of these levers is in close proximity to a post or rod, so that when moved in one direction the lever is tilted and its end slides freely along the post, but when moved in the opposite direction the end of the lever takes into the surface of said rod and movement is blocked. I prefer to notch the engaging end of each lever with a notch in the arc of curvature corresponding to the surface of the rod it engages, and I bias the free or engaging end of each lever, so as to normally throw it into contact with the rod. For this purpose I

prefer to employ a spring of suitable construction preferably placed under the end of the lever on the opposite side of the fulcrum from the engaging or contact end. The two pivoted levers are placed on the top board, strip, or cover on suitable bearings outside the two

rods or posts. The blanks employed are perforated with holes corresponding in position and size to the two or more vertical rods above described, and a diverging notch or channel is cut from the edge of the blank leading into such holes, so that by slightly curving, folding, or bending the blank it may be disengaged from the rods or posts.

The accompanying drawings illustrate my invention.

Figure 1 is a complete view of my invention. Fig. 2 is a cross-section of Fig. 1 in a line drawn through the vertical rods. Fig. 3 shows the arrangement of notches in the blanks to be employed.

B is a back board of wood or card. Rods R, which may be of any metal and either round or polygonal, as shown, are fixed, as at f, to the board B.

C is a top board, support, or cover. Across the top edge there extends a plate of metal P, riveted to the board C, as at r. The board C and strip P are perforated with holes corresponding in shape, size, and position to the rods R, so that the cover C may slide freely on the rods. On the strip P are supported two levers pivoted or hinged, as at P, and having their ends notched to conform to the outline of the posts or rods R, as shown at a. Springs S throw the ends of these levers into contact with the posts or rods R, and while the levers slide downward in contact with the rods R the reverse movement is blocked by reason of the engagement of the ends of the levers with the rods R.

It is desirable to be able to release, remove, and replace any single leaf or sheet of a series, and for this purpose I slot or notch the edges of the leaves with cuts n, which diverge from points or perforations in the sheets corresponding in position to the position of the posts R, so that by folding or bending a sheet it may be released and again replaced in the same manner.

What I claim, and desire to secure by Letters Patent, is—

In a binder for leaves, the combination of a rigid bottom piece or back, vertical rods or posts supported thereby, a perforated rigid companion piece or strip threaded upon the rods

vertical rods, and a lever for each post hinged to the companion piece upon a transverse pivot at a point between the vertical rod and the end of the companion piece or strip, a notch in the contact end of each lever conforming to the outline of its vertical rod, the exterior end of each lever forming a thumb

contact located near the end of said strip, substantially as and for the purpose described.

FRANK E. ROBINSON.
